UNITED STATES PATENT OFFICE

BENJAMIN T. BROOKS, OF GREENWICH, CONNECTICUT, AND EUGENE J. CARDARELLI, OF NEWARK, NEW JERSEY, ASSIGNEES, BY MESNE ASSIGNMENTS, TO STANDARD ALCOHOL COMPANY, OF WILMINGTON, DELAWARE, A CORPORATION OF DELAWARE

PROCESS FOR SULPHATING OLEFINES

No Drawing.

Application filed December 10, 1930. Serial No. 501,469.

This invention relates to the sulphation of propylene and will be fully understood from the following description:

The propylene to be sulphated may be obtained from any available source as, for example, from the products of destructive distillation of materials containing carbon and hydrogen. It may conveniently be obtained by the pyrolysis of shale oil or petroleum, and these oils may be hereinafter generically designated as "mineral oils".

Propylene occurring in the gases produced by cracking petroleum oil has been commercially sulphated either by the use of concentrated sulphuric acid at relatively low temperatures or of more dilute sulphuric acid at or about normal temperatures. In general, elevation of temperature or increase of acid concentration individually favor more rapid reaction, and within the time limitations of commercial apparatus more complete conversion. There are, however, practical limits to the extent to which these two factors may be increased either singly or in combination, for too high an acid concentration and/or temperature results in excessive polymerization of propylene which material is thereby lost to the sulphation reaction. For this reason relatively low temperatures and artificial refrigeration have been necessary when employing concentrated sulphuric acid. Conversely, even at normal temperatures it has been necessary to employ a strength of acid which results in considerable polymerization and loss of propylene.

We have found, however, that we are enabled to operate satisfactorily with a lower combination of acid concentration and temperature by suitable control of the partial pressure of the propylene. The pressure referred to is independent of the gross or total pressure of the materials present and is the actual pressure exerted by the proportion of propylene present. It is frequently necessary to carry out the sulphation in gas phase, particularly where the raw material contains a minor proportion of propylene. Even in this case, however, by adjustment of the partial pressure of the propylene present uniform sulphating conditions may be

obtained compatible with the employment of an acid concentration and temperature in combination at which highly satisfactory reaction velocities and conversion yields result, together with a very substantial inhibition of the usual polymerization loss. In general, we operate with propylene partial pressures in excess of 50 pounds gage to the square inch. Generally speaking, with these partial pressures we may employ acid of 69 70 to 80%, H_2SO_4 content, at temperatures of from 10 to 40° C. While the acid concentrations and temperatures recited are co-extensive throughout the entire range, viz, the higher acid concentration may if desired 69 be employed in combination with a higher 69 temperature and vice versa, for best results we prefer to employ an acid concentration of from 75 to 80% at a temperature of from 70 to 30° C., and an acid concentration of 70 from 70 to 75% at a temperature of from 25 to 40° C. Better results may be obtained by the employment of partial pressures in excess of 100 pounds per square inch. With either partial pressure however, when the 70 acid concentration and temperature are fixed uniform sulphation may be obtained regardless of the amount of diluent gases which may be present.

It is a further advantage of the prescribed control of the partial pressure of the propylene that it is thereby rendered possible in a single stage reaction to form dipropyl sulphate by contacting the propylene with aqueous sulphuric acid. The dipropyl sulphate is intrinsically valuable as an intermediate in chemical reactions and as a source material for the generation of pure isopropyl alcohol of exceptional high quality. For the generation of the dipropyl sulphate it is necessary to maintain a partial pressure in excess of 50 pounds to the square inch and to maintain the sulphuric acid and propylene in contact until the acid has been converted at least in part into dipropyl sulphate. Partial pressures in excess of 100 pounds to the square inch favor the conversion. For this purpose acid concentrations of from 65 to 85% may be employed at temperatures ranging from 10 to 45° C. The dipropyl sulphate 100

- generated is an oily material only limitedly soluble in the solution of sulphuric acid or mono propyl sulphate. It may be separated therefrom by stratification and thereafter hydrolyzed by digesting or distilling the same of water to produce isopropyl alcohol. Alternatively, the hydrolysis of the dipropyl sulphate may be accomplished in the presence of the aqueous sulphuric acid by adding water followed by digestion or distillation. It is particularly desirable, preliminary to the sulphation of the propylene, to remove either by chemical or physical means substantially all the olefines of more than 3 carbon atoms to the molecule. This results in an improved sulphating efficiency where the effort is to make either mono or dipropyl sulphate, but is particularly helpful where the effort is to generate the dipropyl sulphate as it avoids contaminating the dipropyl sulphate with polymers which complicate the recovery of isopropyl alcohol and further tend to impart an undesirable odor to the finished material.
25. The generation of the dipropyl sulphate may be carried out with propylene which is either in liquid or gas phase. The preferred procedure for this purpose consists in separating from the cracked materials a fraction 30 the olefine content of which consists predominantly of olefines of 3 carbon atoms to the molecule. For every stipulated partial pressure of propylene this effects a reduction in the total pressure required with corresponding economies in constructing and/or operating the equipment. These economies and the chemical efficiency of the operation are further enhanced by the employment of a highly cracked raw material which yields a 35 hydrocarbon fraction consisting predominantly of olefines of 3 carbon atoms to the molecule. In our preferred procedure the raw material is the normally gaseous olefines produced by cracking mineral oil in vapor phase at temperatures between 1000 and 40 1200° F., preferably between 1050 and 1150° F. From this raw material we separate by distillation, specifically rectification, a hydrocarbon fraction consisting predominantly 45 of olefines of 3 carbon atoms to the molecule. In actual practice this fraction contains only minor proportions of olefines of more or less than 3 carbon atoms to the molecule and will ordinarily contain not less than 80% of 50 propylene.
55. As a specific example of the application of our process, such a fraction was agitated at 25° C. with an aqueous solution of sulphuric acid containing 80%, H_2SO_4 . The partial pressure of the propylene was about 100 pounds per square inch. When a quantity of gas corresponding to 2 mols of propylene to one of sulphuric acid had been added, the introduction of propylene was discontinued 60 and the agitation was thereafter continued

for about one hour. The reaction was thereafter diluted with about six volumes of water, whereupon di-isopropyl sulphate separated as a dark colored oil very sparingly soluble in the aqueous layer. When the diluted material was warmed and agitated, the di-isopropyl sulphate hydrolyzed rapidly and substantially pure isopropyl sulphate was separated by distillation.

70. In practice it may not be desirable under all conditions to attempt to generate the theoretical quantities of dipropyl sulphate based on the acid taken as the reaction velocity diminishes as this condition is approached. The major part of the acid may, however, be conveniently converted at favorable reaction velocities to dipropyl sulphate. Some dipropyl sulphate is formed under the conditions outlined even where two mols of acid are present for each mol of propylene, but the proportion of dipropyl sulphate produced is favored by the employment of less than two mols of acid for each mol of propylene. Somewhat less than three-halves mols of acid 75 for each mol of propylene is favored in commercial practice.

90. Where the propylene is treated in gas phase the sulphation reaction is preferably carried out in a column of the bubble tower type preferably equipped with plates, bell-caps and downflow pipes so as to maintain the continuous counter-current contact of the gas and acid. We find that the bubble tower type of contactor is highly preferable to the packed tower, inasmuch as it permits the maintenance of a definite volume of acid in the tower at all times and thereby enables us to maintain any desired rate of flow of acid and gas while simultaneously permitting complete control of the time during which the materials are in contact. The column should, of course, be suitably equipped to operate at the pressures required, and superior results are obtainable in consequence of the complete control of the concentrations and volumes of acid and of the simultaneous volumes and concentrations of ethylene which are made possible by carrying out the reaction within the range of pressures hereinbefore specified.

100. The foregoing specific description is for purposes of illustration and not of limitation. It is therefore our intention that the invention be limited only by the appended claims 105 or their equivalents in which we have endeavored to claim broadly all inherent novelty.

110. We claim:

1. Process of sulphating propylene, which 115 comprises contacting same in gas phase with aqueous sulphuric acid of from 65 to 80%, H_2SO_4 content, while maintaining a temperature at which sulphation of propylene takes place, and maintaining the partial 120

pressure of said propylene at not less than 50 pounds gage per square inch.

2. Process according to claim 1, carried out at a partial pressure of propylene not less than 100 pounds per square inch.

3. Process of sulphating propylene, which comprises contacting same in gas phase with aqueous sulphuric acid of from 65 to 80%, H_2SO_4 content, at a temperature of from 10 to 40° C., while maintaining the partial pressure of said propylene in excess of 50 pounds gage per square inch.

4. Process according to claim 3, in which the partial pressure of the propylene is maintained at not less than 100 pounds gage per square inch.

5. Process of sulphating propylene, which comprises contacting same under pressure with aqueous sulphuric acid of from 65 to 85%, H_2SO_4 content, while maintaining the partial pressure of said propylene at not less than 50 pounds gage per square inch, maintaining a temperature at which sulphation

of propylene takes place, and maintaining such contact until the acid is at least in part converted into dipropyl sulphate.

6. Process according to claim 5, in which the partial pressure of the propylene is maintained at not less than 100 pounds gage per square inch.

7. Process of sulphating propylene, which comprises contacting same under pressure with aqueous sulphuric acid of from 65 to 85%, H_2SO_4 content, at a temperature of from 10 to 40° C., while maintaining the partial pressure of said propylene at not less than 50 pounds gage per square inch, and maintaining such contact until the acid is at least in part converted into dipropyl sulphate.

8. Process according to claim 7, in which the partial pressure of the propylene is maintained at not less than 100 pounds gage per square inch.

BENJAMIN T. BROOKS.
